**YARN FEEDING AND CHANGING MECHANISM
FOR CIRCULAR KNITTING MACHINES**

Alfred Percy Saunders, Leicester, England, assignor to Wildt Mellor Bromley Limited, Leicester, England, a British company

Filed Oct. 4, 1957, Ser. No. 688,161

Claims priority, application Great Britain Oct. 15, 1956

11 Claims. (Cl. 66—140)

This invention relates to yarn feeding and changing mechanism for circular knitting machines of the cylinder and dial type, and has reference particularly to yarn feeding and changing mechanism of the kind including a plurality of yarn guiding feeders each of which has associated therewith an individual yarn placing element, and wherein the said elements are operable selectively and each adapted, when so operated, not only to contact and move the companion yarn feeder from a non-feeding position adjacent to yarn trapping and severing means into a feeding position at which a yarn is favourably disposed by the feeder for introduction to needles of one of the two sets in the machine, but also to act on the yarn so disposed and thereby displace it in a radially inward direction suchwise as to effect such introduction.

The invention may be applied to cylinder and dial machines of the rotary cam box type, i.e. of the type wherein the cylinder and the dial are stationary whereas the cylinder cam box and the dial cam plate furnished with the cams necessary for actuating the sets of cylinder and dial needles, revolves together.

There is, however, no limitation in this respect since the invention may also be applied to cylinder and dial machines wherein the cylinder cam box and dial cam plate are stationary and the cylinder and the dial rotate together.

The object of the present invention is to provide general improvements in the construction, operation and control of a yarn feeding and changing mechanism of the kind concerned as will be hereinafter described.

A particular aim is to enable the improved mechanism to feed to the needles different types of yarn or thread such as fine nylon thread, elastic yarn, yarns of wool and many other combinations, and efficiently to effect changes as from a yarn or thread of one character to a yarn or thread having quite different characteristics.

The invention may advantageously be embodied in a horizontal striping attachment.

In the improved yarn feeding and changing mechanism constituting this invention there is an independent yarn trapping and severing unit to each yarn feeder and associated yarn placing element, and for actuating each such element and also a member for operating the corresponding individual trapper there is provided a common actuator which is adapted, when selected and moved to initiate introduction of a yarn to appropriate needles, to be advanced in two separate and defined stages, viz a first stage during which the common actuator moves the yarn placing element into its operative position and, in so doing, first causes the said element to contact the companion yarn feeder and displace it from its non-feeding to its feeding position, and a second stage at which the corresponding trapper operating member is operated suchwise as to open the relevant trapper and thereby release the yarn introduced to the needles.

For the sake of simplicity in the following further de-

2

scription and in the appended claims the yarn placing elements will be referred to as "yarn placers."

As will be appreciated, there is a plurality of the common actuators, one to each yarn feeder and corresponding yarn placer and independent trapping and severing unit, and these actuators are adapted to be selectively operated, through the medium of control connections of any suitable character at the dictates of timing mechanism.

10 Each common actuator may advantageously be suitably biassed, e.g. by a spring, towards its normal inoperative, i.e. un-selected, position and arranged to be advanced against the biassing means. In this regard, an individual spring-influenced check pawl or detent may be provided for co-operation with spaced formations in each actuator, these formations, two in number, serving to define the two separate stages in the advance of the actuator to its fully operative position. That is to say, engagement of the check pawl or detent into the first of the two formations will determine and define the first stage of the advance of the actuator to effect introduction of the relevant yarn to the needles of the appropriate set, whereas the second stage of such advance to open the corresponding trapper and release the said 15 yarn will be determined and defined by the engagement of the check pawl or detent in the second formation. When engaged in said second formation, the check pawl or detent functions to hold the actuator fully forward with the corresponding yarn feeder in its feeding position 20 which latter is maintained for as long as the yarn is required to be fed to the needles. For effecting withdrawal of such yarn feeder from knitting as, for instance, at a yarn change, the check pawl or detent is moved under suitable control against the spring action influencing it, as a consequence of which the common actuator is released for rapid return to its inoperative position. Simultaneously with this return, the corresponding yarn 25 placer and the associated yarn feeder, conveniently influenced by a common spring, are retracted to their inoperative positions.

In accordance with a feature of the invention, provision is made for lost motion between each yarn placer and the corresponding actuator during the second stage 30 of advance of the latter. The purpose of this is, of course, to enable a yarn feeder and the associated yarn placer to remain stationary in their feeding positions whilst the actuator is moving forward to complete its second stage of advance at which point it effects actuation of the trapper operating member and opening of the trapper to release the newly introduced yarn. In this way the said yarn is enabled to be safely taken and knitted by a few (say two or more) of the needles of the appropriate set before the yarn is released from the 35 trapper.

According to a further feature of the invention, an individual spring-influenced check detent, separate and distinct from the corresponding actuator check pawl or detent, is provided in conjunction with each trapper operating member for the purpose of maintaining the latter in the position to which it is moved by the said actuator during the second stage of the advance thereof. Thus, the check detent functioning in conjunction with each trapper operating member is arranged to act on the latter suchwise as to hold the relevant trapper open for as long as an introduced yarn is required to be fed to the needles.

In order that the invention may be more clearly understood and readily carried into practical effect, a specific constructional example of a striping mechanism arranged for feeding a selected one of a plurality, say four,

yarns to the dial needles of such a machine equipped with a stationary cylinder and dial will now be described with reference to the accompanying drawings, wherein,

Figure 1 is a vertical sectional view, partly in side elevation, illustrating the stiper mechanism shown in relation not only to the cylinder and dial of the machine but also to the means for controlling the said mechanism,

Figure 2 is a front view of the stiper unit per se as seen in the direction of the arrow A in Figure 1,

Figure 3 is a rear view of the unit as seen in the direction of the arrow B in Figure 1,

Figure 4 is a detail front view of the independent yarn trapping and severing units as viewed in the direction of the arrow C in Figure 1,

Figure 5 is a cross sectional view taken on the line V—V of Figure 4,

Figure 6 is an exploded perspective view depicting the various components of one of the trapping and severing units,

Figures 7 and 8 are two comparative diagrammatic side views each showing a yarn feeder, a corresponding yarn placer, movable scissor and trapper blades, a trapper operating lever, a common actuator, a corresponding actuator check pawl or detent and a check detent associated with the trapper operating lever, the specified parts being shown in the positions they occupy at the termination of the first stage (Figure 7) and of the second stage (Figure 8) of advance of the said common actuator when selected, and

Figure 9 is a perspective view corresponding to Figure 8.

Like parts are designated by similar reference characters throughout the drawings.

Referring to Figure 1, it will be seen that the circular knitting machine to which the stiper mechanism now to be described is applied includes a stationary cylinder 1 furnished with cylinder needles such as 2 and a stationary dial 3 equipped with dial needles such as 4. Surrounding the cylinder 1 is an annular cam box 5 which is mounted upon a rotary carriage 6. Cams 7 and 8 attached respectively to the cam box 5 and the rotary carriage 6 are arranged to provide between them a track T into which extend knitting butts 9 on the cylinder needles 2. Above the stationary dial 3 there is a rotary dial cam-plate 10 to the underside of which are attached cams 11 and 12 arranged to provide between them a track T' into which extend knitting butts 13 on the dial needles 4.

As depicted in Figure 1, the control mechanism of the machine includes a peripherally notched chain wheel 14 which is secured upon an axle 15 and is adapted to be racked round step by step by means of a pawl 16 co-operable with a ratchet wheel 17 rigid with the said wheel. Extending over the chain wheel 14 is a timing or patterning chain 18 furnished with lugs 19.

The stiper unit, indicated generally at 20, is mounted upon and arranged to revolve together with the rotatable cylinder cam box 5 and the dial cam-plate 10. In this regard the said unit may be supported upon a bracket or brackets (not shown) carried by any appropriate rotary part of the knitting head of the machine.

The unit comprises two suitably spaced and parallel vertical side plates 21 and 22 (Figures 2 and 3) which are connected by interposed transverse blocks or plates 23, 24, 25, 26 and 27 which are located in different horizontal planes and function also for the purpose hereinafter to be explained. The framework of the stiper unit 20, which is rectangular in plan, is directed radially inwards with its lower portion 20a located adjacent to the cylinder and dial needles 2 and 4. Regarded from either side, the upper portion of the framework is rectangular in shape whilst its lower portion 20a is of downwardly tapering form (see Figure 1).

Opposed faces of the transverse blocks or plates 23

and 24, on the one hand, and 25 and 26 on the other hand, which blocks are spaced apart heightwise and secured by screws 28 in the upper portion of the framework, are suitably grooved or slotted longitudinally at 23a, 24a, 25a and 26a suchwise as to provide guideways for a plurality of horizontally movable actuator slides 29. As viewed from either end in Figures 2 and 3, or in cross-section, however, these actuator slides 29 are arranged vertically in close side-by-side relation. Each actuator slide 29 is longitudinally slotted at 30 to accommodate a short tension spring 31 the leading end 31a of which latter is anchored to the front vertical edge of the slide. The rear ends 31b of the springs 31 are secured to a split pin 32 which extends transversely through the longitudinal slot 30 and is fixed in the side plates 21 and 22. Projecting outwardly from the rear vertical edge of each actuator slide 29 is a tail butt 33, these butts being arranged one above the other in different horizontal planes and indicated more clearly in Figure 3. Thus, by pressing inwardly upon the end of a selected tail butt 33, the corresponding actuator slide 29 is advanced against the action of its controlling tension spring 31. In the upper horizontal edge of each actuator slide there are formed two small V-shaped notches 34 and 35 arranged one closely behind the other. A check pawl 36 is provided for engagement successively in these notches 34 and 35, whenever an actuator slide 29 is advanced against its spring action as described. That is to say, there is one check pawl 36 to each actuator slide 29, these check pawls being mounted side by side for pivotal movement independently about a transverse pivot pin 37 located between the vertical side plates 21 and 22 of the framework. To expose the notched upper edges of the actuator slides 29 for co-operation with the check pawls 36, and at the same time provide the necessary space for accommodation of the latter, the longitudinally grooved or slotted upper transverse guide blocks or plates 23 and 24 assisting in the guidance of said actuator slides are spaced apart longitudinally with a space S between them (see Figure 1). Each slide check pawl 36 is connected with a tension spring 38 serving to bias it downwardly into contact with the notched upper edge of the corresponding actuator slide 29. Advance of a selected slide 29 accordingly takes place in two separate and distinct stages defined by engagement of the relevant spring-influenced check pawl 36 successively in the two V-shaped notches 34 and 35.

For tripping all of the check pawls 36 simultaneously there is provided a horizontally disposed slidable release plunger 39 which is mounted upon the top of the transverse guide block or plate 23. The transverse dimension, i.e. width, of the operative inner end 39a of this release plunger 39 is sufficient to enable the plunger, when pushed in, to act on and trip all of the check pawls 36 by turning them against the action of their tension springs 38. The check pawl release plunger 39 is itself controlled by one or more compression springs such as 40. The outer end 39b of the plunger 39 is of less width than its operative end 39a and, as shown in Figures 1 and 3, projects from the framework at a location somewhat above the uppermost butt 33 of the series of butts 33 on the actuator slides 29. It is to be clearly understood, however, that whenever the check pawl release plunger 39 is pushed in, the only actuator slide 29 to be released and permitted to return under spring action to its inoperative position will be that whose tail butt 33 is no longer pressed upon and held in by a common selector 41 (hereinafter to be described), i.e. the slide corresponding to an outgoing yarn. On the other hand, a freshly selected actuator slide 29 the butt 33 of which, as shown in Figure 8, is engaged by the common selector 41 at the moment the check pawls 36 are tripped will remain in its advanced position.

In the lower horizontal edge of each actuator slide 29 is formed a recess 42 the rear end of which provides

a shoulder 43 for contact with a corresponding trapper operating lever 44 hereinafter to be described.

Mounted to fulcrum about a transverse pivot pin 45 set in the framework, at a location in front of and a little above the lower horizontal edges of the actuator slides 29, is a plurality of depending and individually operable yarn placers 46—one to each such slide. When in its normal retracted (non-feeding) position depicted in full lines in Figure 1, each yarn placer 46 extends downwardly and rearwardly somewhat so that a protuberant yarn-engaging nose 47 provided at its lower extremity is withdrawn within the framework. A lower marginal portion of each yarn placer 46 adjoining its nose 47 is bent upwardly to form a channel 48—shown more clearly in Figure 9. Rigidly secured to the upper end of each yarn placer 46, at the same side thereof as the channel 48, is a rearwardly directed operating element 49 having an upwardly extending tail 50 for contact by the front lower corner of the corresponding actuator slide 29 (see Figure 1). The normal retracted position of each yarn placer 46 is determined by contact of the rear inclined edge 51 of its operating element 49 with an inclined frontal face 52 of the front longitudinally grooved transverse block or plate 26 assisting to support and guide the actuator slides 29.

Provided at the channelled side of each yarn placer 46 is a comparatively thin companion yarn feeder 53 in the form of a lever with a yarn guiding lower extremity 54. These yarn feeders are, at or near their upper ends, mounted to fulcrum about a transverse pivot pin 55 which is set in the framework at a location substantially below and to the rear of the transverse pivot pin 45 constituting the fulcrum of the yarn placers 46. Each yarn feeder 53 extends forwardly and downwardly from its fulcrum and passes through, and in contact with the bottom, of the channel 48 formed at the lower extremity of the companion yarn placer 46. The lower extremity 54 of each yarn feeder 53 projecting from the leading end of the channel 48 extends vertically downwards (when the feeder is in its retracted or non-feeding position indicated in full lines in Figure 1). Each yarn placer 46 and the companion yarn feeder 53 are influenced by a single tension spring 56 connecting the two together. As shown more clearly in Figure 9, one end of this return spring is anchored to a lug 57 provided on the upper end of the yarn feeder 53 adjacent to its fulcrum 55 whereas the opposite end of the spring is connected to a pin 58 fixed in the underside of the operating element 49 rigid with the yarn placer 46. Now during the first stage of the advance of a selected actuator slide 29, determined by engagement of the corresponding check pawl 36 in the first V-notch 34 in said slide, the lower front corner of the latter pushes against the rear inclined edge 51 of the operating element 49 rigid with the corresponding yarn placer 46 and pushes this forward against the action of the relevant spring 56. As the placer 46 turns about its fulcrum 45 the operative yarn engaging nose 47 thereof swings forward in a practically straight, but slightly arcuate, path above and clear of advanced dial needles 4. At the same time, the companion yarn feeder 53 is acted upon by the bottom of the channelled portion 48 of the yarn placer 46 and is turned upwardly about the yarn feeder fulcrum 55 so that the yarn guiding extremity 54 of the said feeder moves along a near-vertical arcuate path in front and clear of the hooks of the advanced dial needles. Thus, as will be appreciated, this conjoint movement of the nose 47 of the yarn placer 46 and the yarn guiding extremity 54 of the yarn feeder 53 causes the relevant ingoing yarn Y (see Figure 9) to be first moved by the feeder into a favourable position for introduction to the dial needles 4, and then to be pushed forward by the placer so that a straight length of the yarn extending upwards from the corresponding trapper is positively passed between dial needles to ensure engagement of the yarn with the needle hooks. As the

actuator slide 29 reaches the end of its first stage of advance, the upwardly extending tail 50 on the operating element 49 rigid with the yarn placer 46 engages beneath the lower horizontal edge of the slide as illustrated in Figure 7. Accordingly, continued forward movement of the selected slide 29 during the second stage of its advance will take place independently of the yarn placer 46 which, during this stage, will remain stationary. This will be apparent from a comparison of Figure 8 with Figure 7, and the arrangement is such as to provide lost motion between the slide and the placer.

In a case where the machine is equipped with Jacquard patterning mechanism, an ingoing yarn may be introduced to the needles at a gap in the needles resulting from pre-determined ones of the latter being unselected.

In the specific example illustrated, the lower ends of the vertical side plates 21 and 22 of the framework of the striper unit are connected by a horizontal transverse plate 56 surmounted by a vertically slotted block 57 constituting a common carrier for the independent trapping and severing units U. These units U are located immediately beneath the lower yarn-guiding extremities 56 of the yarn feeders 53. Common to all of the trapping and severing units U is a transverse spindle 58 upon which are pivotally mounted pairs of conjointly movable trapper blanks 59 and scissor blades 60. Viewing the trapping and severing units U from the front and side, as in Figures 4 and 5, respectively, it will be seen that each such unit comprises a fixed cutter block 61 at the right-hand side of the unit, when an immediately adjacent pivoted scissor blade 60 for co-operation with the fixed cutter block, next a fixed trapper part 62 and, adjacent to the latter and at the left-hand side of the unit, a pivoted trapper blade 59 which is rigid and movable together with the corresponding pivoted scissor blade 60. The unit, the component parts of which are more clearly shown in exploded condition in Figure 6, is completed by the provision of a blade spring 63 which, by exertion of pressure laterally upon the left-hand side of the pivoted trapper blade 59, provides sufficient friction between the latter and the fixed trapper part 62 to exercise the necessary grip upon a yarn withdrawn from knitting. Each pivoted scissor blade 60 is extended rearwardly to provide an arm 64 and this blade and also its companion trapper blade 59, are articulated, by means of a pin-and-slot connection 65, 66, with the lower end of a corresponding upwardly and rearwardly extending trapper operating lever 44.

All of the trapper operating levers 44 are mounted to turn about the same transverse pivot pin 55 constituting the fulcrum of the yarn feeders 53. Anchored to the outer end of each pivoted scissor blade actuating arm 64 is one end of a tension spring 70 the opposite end of which latter is anchored to a transverse pin 71 carried by the side plates 21 and 22 of the framework. Turning movement of one of the arms 64 against the spring action simultaneously opens both the relevant trapper and the adjoining scissor device. On the other hand, release of such arm permits it to turn in the reverse direction under the reaction of the corresponding spring 70 suchwise as smartly to close the trapper and scissor device. An outgoing yarn trapped in a trapper is crimped by virtue of extending around the edge of the fixed trapper part 62 and between the outer side of the latter and the inner side of the pivoted trapper blade 59 as well as between the inner side of the said fixed trapper part 62 and the opposing face of the pivoted scissor blade 60.

The upper end of each pivoted trapper operating lever 44 is, as shown more clearly in Figure 9, formed with an upwardly directed extension 72 extending beyond the fulcrum 55, and this extension projects through a slot 73 formed in the rear one 25, of the two lower grooved blocks or plates supporting and guiding the actuator slides 29. In fact, the extremity of the said upwardly directed extension 72 of each lever 44 is arranged to be

in the path of the shoulder 43 produced by recessing at 42 the lower horizontal edge of the corresponding actuator slide 29. Consequently, during the second stage in the advance of a selected actuator slide 29, the relevant shoulder 43 acts on the upwardly directed extension 72 of the corresponding trapper operating lever 44 and pushes this extension forwards as depicted in Figure 8 with the result that the lower end of the said lever is drawn back to turn the arm 64 articulated thereto and so open the trapper 59, 62 and scissor device 60, 61 against spring action.

For maintaining a trapper 59, 62 and scissor device 60, 61 open for as long as may be desired, there is provided, in association with each trapper operating lever 44, a spring influenced pivoted detent 74 (Figures 1 and 9) which, whenever the upwardly directed extension 72 of the lever is pushed forwards as just described, snaps into position behind a rearwardly extending projection 75 on the lever. All of these spring-influenced detents 74 are pivotally mounted individually upon a transverse spindle 76 set in the framework, and the said detents are provided with depending lugs 77 adapted to be acted on simultaneously by a second release plunger 78. This plunger 78, like the hereinbefore described first release plunger 39, is mounted upon the transverse block or plate 27 and is provided with an operative inner end 78a sufficiently wide to act on all the detents 74 together. As shown in Figure 3, the outer end 78b of the second release plunger 78, which latter is controlled by a compression spring 80, is of a somewhat narrower width and projects outwardly from the framework beneath the superimposed butts 33 on the actuator slides 29.

For action selectively upon the tail butts 33 of the actuator slides 29 there is provided a profiled portion of, or part on, the common selector 41 in the form of a striker plate which is adapted to be shifted up or down, under suitable control, either into one or another of the aforementioned different planes or into a neutral position (indicated in Figure 1) below and clear of the tail butts 33. When the common selector is in the neutral position the mechanism is inoperative and no yarn change can take place. But whenever, on the other hand, the selector 41 is moved into one of the aforementioned planes, then relative rotation between the yarn feeding and changing mechanism and the said selector will cause the inner end of the later to act on the desired tail butt 33 to advance the selected actuator slide 29 and thereby initiate either introduction of a yarn or a yarn change.

The plungers 39 and 78 for tripping first the check pawls 36 and then the independent pivoted check detents 74, and so effecting first withdrawal from knitting of an outgoing yarn and then trapping and cutting of this yarn, are operated respectively by striker cams or cam-like members 82 and 83 associated and movable conjointly with the common selector 41. The timing is such, however, that the tripping of the plungers 39 and 78, is delayed until the new yarn has been introduced by selection of the relevant actuator slide 29.

As will be seen in Figure 1, the common selector 41 in the specific example illustrated is mounted upon a carrier 84 which is slidable to various positions heightwise along a vertical guide post (not shown), the carrier being guided by an additional post 85, and the selector resting against a guide plate 86. The guide posts are secured in a fixed bracket 87 to the underside of which is attached a sleeve 88, for the guidance of a vertically movable rod 89. The upper end of this rod is articulated to the selector carrier 84 whilst at its lower end the said rod impinges on a control lever 90 having a toe 91 arranged to be acted upon by lugs such as 19 of different heights on the timing or patterning chain 18. The striker cam 82 extends upwardly from and is rigid with the common selector 41. The striker cam 83, on the other hand, is secured to a carrier 92 which is controlled by a compression spring

93 and is adapted to be held down against the spring action (with the striker cam 83 below and clear of the plunger 78) by means of the selector carrier 84 whenever the selector 41 is in its neutral position. But when the selector 41 is shifted up into any one of the planes concerned, the carrier 92 will be released and permitted to move up under the influence of the spring 93 to an extent sufficient to dispose the striker cam 83 in the path of the plunger 78.

10 Thus, assuming one of the striping yarns is already being fed to the dial needles 4, then, to effect a yarn change by substitution of the feeding yarn by another of the striping yarns, the common selector 41 is first shifted, up or down, as the case may be, out of the plane in which it engages the tail butt 33 of the previously selected slide 29 into another plane in which it will engage the butt of the newly selected slide. Then, after the new yarn has been introduced to and safely taken by a few needles, the first release plunger 39 is pressed in as a consequence of 15 which the actuator slide corresponding to the yarn to be withdrawn is released to effect retraction of the relevant yarn placer 46 and companion yarn feeder 53 to their non-feeding positions. This action lays the outgoing yarn across the appropriate trapper and severing unit U, whereupon the second release plunger 78 is immediately pressed in to trip the appropriate trapper operating lever 44 and so close the corresponding trapper and scissor device to trap and sever this yarn.

20 For lifting the yarn feeders 53 manually as occasion may demand there is provided an element 94 which, as shown in Figure 1, is secured to a spindle 95 furnished with a knob 96 (see Figures 2 and 3).

25 When applied to a machine of the rotary needle cylinder and dial type, the herein described yarn feeding and changing mechanism would be stationary and the control means would be so arranged as to operate in time with the cylinder and dial.

30 I claim:

1. In a circular knitting machine of the cylinder and dial type, in combination, a cylinder; a set of needles in said cylinder; a dial associated with and concentric with respect to said cylinder; a further set of needles in said dial arranged to co-operate with the needles in the cylinder in the production of knitted fabric; and a yarn feeding and changing mechanism comprising a plurality of yarn feeders pivotally mounted side by side, adjacent to the cylinder and dial, each of said feeders adapted to move upwardly from a non-feeding position into a feeding position; a plurality of corresponding selectively operable yarn placers arranged in contact with said yarn feeders and pivotally mounted side by side for movement radially inwards and outwards with respect to the needles; an independent yarn trapping and severing unit for each yarn feeder, said unit comprising a trapper having fixed and pivoted trapper elements and a cutter having fixed and pivoted scissor elements, levers which are mounted to pivot independently of, but about the same axis as, the yarn feeders and are pivotally connected to the pivoted trapper and scissor elements for operating the same, common actuator slides mounted side by side each for pushing against and actuating a yarn placer and hence also the yarn feeder in contact therewith, as well as the corresponding trapper and scissor operating lever, each of said slides having in one of its longitudinal edges two spaced formations, an individual spring influenced check pawl for engagement successively in said spaced formations of each slide at required times, springs biasing the actuator slides in a radial direction away from the common axis of the cylinder and dial, an intermittently movable timing chain, and control connections between said timing chain and the common actuator slides for selectively advancing said slides against the biasing springs, each of the actuator slides when so advanced moving in two separate stages defined by successive engagement of

the relevant check pawl in the two spaced formations in the slide.

2. In a circular knitting machine of the cylinder and dial type, a combination according to claim 1 wherein there is lost motion between each yarn placer and the corresponding common actuator slide, during the second stage of advance of the latter, whereby the said placer and the companion yarn feeder remain stationary in their operative positions while the actuator slide is advancing to complete its second stage of advance to effect actuation of the corresponding trapper and scissor operating lever.

3. In a circular knitting machine of the cylinder and dial type, a combination according to claim 1, wherein an individual spring influenced check detent, separate and distinct from the corresponding actuator check pawl is provided in conjunction with each trapper and scissor operating lever to maintain the latter in the position to which it is moved by the corresponding common actuator slide during the second stage of the advance thereof.

4. In a circular knitting machine of the cylinder and dial type, a combination according to claim 3 including spring means for each trapper and scissor operating lever whereby whenever an actuator slide moves during the second stage of an advance, it actuates the relevant trapper and scissor operating lever against the spring action and the corresponding check detent is automatically disposed to hold said lever in a loaded condition, and also including control means for triggering of a check detent associated with a loaded trapper and scissor operating lever whereby when a detent is so triggered, the corresponding trapper and scissor operating lever is released under the spring action to close the trapper.

5. In a circular knitting machine of the cylinder and dial type, in combination, a cylinder; a set of needles in said cylinder; a dial associated with and concentric with respect to said cylinder; a further set of needles in said dial arranged to co-operate with the needles in the cylinder in the production of knitted fabric, and a yarn feeding and changing mechanism comprising a plurality of yarn feeders pivotally mounted side by side adjacent to the cylinder and dial for movement such that its yarn guiding extremity moves up along an upright arcuate path from a non-feeding position into a feeding position clear of the hooks of the dial needles, and vice versa, a plurality of corresponding selectively operable yarn placers disposed in contact with said yarn feeders and pivotally mounted side by side for movement radially inwards and outwards along a slightly arcuate path with respect to the needles, each yarn placer when so moved inwardly first raising the companion yarn feeder into its feeding position and then introducing a straight length of yarn extending between said feeder and the corresponding trapper to the dial needles, an independent yarn trapping and severing unit for each yarn feeder, said unit comprising a trapper having fixed and pivoted trapper elements and a cutter having fixed and pivoted scissor elements, levers which are mounted to pivot independently of but about the same axis as the yarn feeders and are pivotally connected to the pivoted trapper and scissor elements for operating the same, common actuator slides mounted side by side and each having formations for pushing against and actuating a yarn placer, and hence also the yarn feeder in contact therewith, as well as the corresponding trapper and scissor operating lever, each of said slides having in one of its longitudinal edges two spaced formations, an individual spring influenced check pawl for engagement successively in said spaced formations of each slide at required times, springs biasing the actuator slides in a radial direction away from the common axis of the cylinder and dial, an intermittently movable timing chain, control means between said timing chain and the common actuator slides for advancing said slides against the biasing springs, each of the actuator slides when so ad-

vanced moving in two separate stages defined by successive engagement of the relevant check pawl in the two spaced formations in the slide, the first stage causing the yarn placer to swing forwards towards the needles and the companion yarn feeder to swing up from its non-feeding position, and the second stage causing the corresponding trapper and scissor operating lever to turn and so open the trapper, and means operable under the control of the timing chain for acting on and disengaging any desired check pawl from the second mentioned formation in the relevant actuator slide to release the latter for return to its inoperative position under the action of its biasing spring.

6. In a circular knitting machine of the cylinder and dial type, a combination according to claim 5 including individual pivoted spring influenced check detents automatically turnable under the spring action into operative positions to maintain the trapper and scissor operating levers in the positions to which they are moved by the corresponding common actuator slides during the second stage of the advance thereof, springs controlling said operating levers and against the action of which the latter are actuated when pushed by said slides during such advance thereof, and control means for turning a selected check detent against the spring action and thereby releasing the corresponding trapper and scissor operating lever to close the trapper and cutter.

7. In a circular knitting machine of the cylinder and dial type, a combination according to claim 5 wherein one end of each trapper and scissor operating lever is articulated by means of a pin and slot connection to the movable trapper and scissor elements of the corresponding independent yarn trapping and severing unit.

8. In a circular knitting machine of the cylinder and dial type, a combination according to claim 7 wherein the movable scissor element of each independent yarn trapping and severing unit is extended beyond the pin and slot connections to provide an arm, and wherein the said movable trapper and scissor elements of said unit are controlled by a spring which is anchored to said arm.

9. In a circular knitting machine of the cylinder and dial type, in combination, a cylinder; a set of needles in said cylinder; a dial; a further set of needles in said dial; and a yarn feeding and changing mechanism including a plurality of side by side yarn feeders for feeding yarns selectively to the needles, a plurality of corresponding side by side selectively operable yarn placers for contacting and moving the companion yarn feeder from a non-feeding position into a feeding position where the yarn is favorably disposed for introduction to needles of one of the two sets in the machine and for acting on the yarn so disposed to displace it in a radially inward direction to effect such introduction, an independent yarn trapping and severing unit for each yarn feeder, said unit comprising a trapper having fixed and movable trapper elements and a cutter having fixed and movable scissor elements, members for operating the individual trappers, common actuators in the form of slides which are arranged side by side and are provided with tail butts disposed in respectively different planes, each of said actuators serving to actuate a yarn placer and the corresponding trapper operating member, a common selector to be moved from a neutral position clear of all the tail butts into a desired one of the aforementioned planes, means for effecting relative rotation between the yarn feeding and changing mechanism and said selector, and control means for moving the selector into a desired plane, whereby whenever the selector is moved into one of said planes the relative rotation will cause the selector to act on the desired tail butt to advance the selected actuator, each of said actuators, when selected and advanced to initiate introduction of a yarn to needles of the aforesaid set being advanced in two separate and defined stages, first causing said placer to contact the

11

companion yarn feeder and displace it from its non-feeding to its feeding position, and secondly operating the corresponding trapper operating member to open the relevant trapper and release the yarn introduced to the needles.

10. In a circular knitting machine of the cylinder and dial type, a cylinder, a set of needles in said cylinder; a dial; a further set of needles in said dial; and a yarn feeding and changing mechanism including a plurality of yarn feeders for feeding yarns selectively to the needles, a plurality of corresponding selectively operable yarn placers for contacting and moving the companion yarn feeder from a non-feeding position into a feeding position where its yarn is favorably disposed for introduction to the needles of one of the two sets in the machine and for acting on the yarn so disposed to displace it to effect such introduction, an independent yarn trapping and severing unit to each yarn feeder, said unit comprising a trapper having relatively movable trapper elements and a cutter having relatively movable scissor elements, members for operating the individual trappers, common actuators for actuating a yarn placer and a corresponding trapper operating member, said actuators being in the form of slides which are provided with tail butts disposed in respectively different planes, a longitudinal edge of each of said actuators having therein two spaced formations, individual spring influenced check pawls for engagement successively in said spaced formations, springs biasing the actuators towards normal inoperative positions, a common selector which is adapted to be moved from a neutral position clear of all of the tail butts into a desired one of the aforementioned planes, means for effecting relative rotation between the yarn feeding and changing mechanism and said selector, control means for moving the selector into a desired plane, whereby whenever the selector is moved into one of these planes, the relative rotation causes the selector to act on

12

the desired tail butt to advance the selected actuator against the relevant biasing spring, each of said actuators, when selected and advanced to initiate introduction of a yarn to needles of the aforesaid set, being advanced in two separate stages defined by engagement of the relevant check pawl successively in the spaced formation in the actuator, first moving the corresponding yarn placer into operative position and causing said placer to contact the companion yarn and displace it to its feeding position and secondly operating the corresponding trapper member to open the trapper and release the yarn introduced to the needles, individual spring influenced check detents, separate and distinct from the common actuator check pawls, for maintaining the trapper operating members in the positions to which they are moved by the corresponding common actuators during the second stage of the advance thereof, a plunger for disengaging actuator check pawls from the second formations in the actuators, a second plunger for tripping the independent check detents associated with the trapper operating members, and striker cams which are influenced by the common selector for operating said plungers.

11. A yarn feeding and changing mechanism according to claim 10 wherein the lower portion of each yarn placer, adjoining a protuberant yarn engaging nose thereof, is bent in such a way as to provide a channel through which the corresponding yarn feeder extends in contact with the bottom thereof, the yarn placer having secured to its upper end an operating element adapted for contact by the corresponding actuator.
